CLAIM

I claim the ornamental design for a stand fan, as shown and described.

DESCRIPTION

FIG. 1 is a perspective view of a stand fan showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The bottom of the stand fan is shaded to indicate a reflective surface.

The broken lines in FIGS. 3 and 7 depict parts of the stand fan that form no part of the claimed design.
